Des. 236,604
Patented Sept. 2, 1975

236,604

SEISMIC ENERGY GENERATOR FLOAT

Clifford D. Dransfield, Dallas, Tex., assignor to Atlantic Richfield Company, Los Angeles, Calif.

Filed Jan. 3, 1974, Ser. No. 430,544

Term of patent 14 years

Int. Cl. D12—06; D13—01

U.S. Cl. D12—62

FIG. 1

FIG. 2

FIG. 3

FIG. 4

FIG. 1 is a perspective view of a seismic energy generator float embodying my design;

FIG. 2 is a top view of the seismic energy generator float of FIG. 1;

FIG. 3 is a side view of the seismic energy generator float of FIG. 1; and

FIG. 4 is a front view of the seismic energy generator float of FIG. 1.

I claim:

The ornamental design for a seismic energy generator float, as shown and described.
